UNITED STATES PATENT OFFICE

VIRGINIUS Z. CARACRISTI, OF BRONXVILLE, NEW YORK, ASSIGNOR TO INTERNATIONAL COMBUSTION ENGINEERING CORPORATION, OF NEW YORK, N. Y., A CORPORATION OF DELAWARE

STATIONARY BOILER

Application filed January 8, 1927. Serial No. 159,805.

This invention relates to stationary boilers, and is especially useful where fuel is burned in a finely divided liquid or gaseous form, as, for example, in the form of pulverized coal.

One of the primary objects of the invention is to provide a stationary boiler installation capable of being fired at the very high rates such as are obtained in locomotive boilers.

Still another object of the invention is to obtain very high capacities in the stationary boiler, as compared to present practice, and this with high efficiency.

Other and more specific objects will appear in connection with the following description of the best form of the invention now known to me.

In the drawings:—

Fig. 1 is a vertical section through a boiler embodying the preferred form of my invention.

Fig. 2 is a section taken on the line 2—2 of Fig. 1 drawn on an enlarged scale.

Fig. 3 is a fragmentary section taken on the line 3—3 of Fig. 1.

Fig. 4 is a fragmentary section taken on the line 4—4 of Fig. 1, and

Fig. 5 is a section taken on the line 5—5 of Fig. 1.

Referring now to the Figures 1, 2 and 3, the reference character A denotes the combustion chamber beneath which is the ash pit B. To the rear of the combustion chamber

is a lower or mud drum 7 above which is an upper drum 8, these two drums being connected by a vertical bank of tubes 9. At the front of the combustion chamber slightly above the level of the drum 7 is a drum 10

and above this, slightly below the level of the drum 8, is another drum 11. The drum 11 is connected with the drum 8 by a plurality of slightly inclined tubes 12 which carry the roof, arch or sheathing brick 13. The drums 10 and 11 are connected by a plurality of pipes 14 which constitute upcomers from the drum 10 to the drum 11, the tubes 12 constituting upcomers from the drum 11 to the drum 8.

The tubes 14 are provided with longitudi-

nally extending fins 15 on each of the two opposite sides, the tubes and fins cooperating to provide a substantially continuous metallic wall which defines the front of the combustion space. This metallic wall is lined with an external sheathing 16 which, by virtue of the cooling effect of the water wall, can be made very light. Certain of the fins on certain of the tubes are interrupted so as to permit of the placing of the burners 17 which feed the fuel to the furnace, it being understood that there are a row of such feed openings located above the drum 10, the number of burners being dependent upon the size of the particular installation.

Connecting the drum 7 to the drum 10 is a row of tubes 18. These tubes are spaced well apart, as shown, for example, in Figs. 2 and 3, in order to permit the refuse particles gravitating out of the fuel and flame stream to freely pass into the ash pit. At their front ends these tubes 18 are provided with fins 19.

The drum 7 and the drum 10 are also connected by groups of tubes C, which tubes are provided with short fins 21 spaced apart longitudinally of the tubes.

The groups of tubes C cooperate with the tubes 18 to provide upstanding hollow wall portions, the interior of which hollow wall portions opens into the space beneath the tubes 18. The fins 21 cooperate with the tubes to provide ports 22 establishing communication between the interior of the hollow upstanding portions and the combustion space above the tubes 18. Air is admitted into the space 23 beneath the drum 10 and the upper ends of the tubes 18 and the group of tubes C, such air entering into the longitudinal channels provided by the group of tubes C, from which space this air enters the combustion space through the ports 22 as will further appear. This air, in traversing the chamber 23, becomes preheated, and may be initially preheated before entering the chamber 23 by any suitable form of air preheater.

Rising from the drum 7 to the drum 11 is a row of tubes 24 diagonally cutting the combustion space very much after the fashion of the circulation tubes employed in a locomotive boiler, which tubes connect the front and

rear water legs of the locomotive boiler. These tubes carry a refractory arch 25 composed of T-shaped bricks socketed on the tubes 24. These tubes have fins 26, as shown in Figure 4, and the legs 27 of the T-shaped bricks are adapted to project inwardly into the space between adjacent fins, in which connection it will be observed that the tubes 24 are relatively widely spaced apart.

10 At the sides of the combustion chamber are tubular water walls D of substantially the same construction as the direct water wall. The finned tubes 28 constituting these side water walls have their ends expanded 15 into the headers 29 and 30, which, in turn, are connected to the drums 10 and 11.

The operation is as follows:

10 The powdered coal with a portion of the air required for combustion is admitted 20 through the burners 17 in a substantially horizontal direction, and the fuel and flame stream takes the course indicated in Fig. 1. Enough air may enter with the fuel to institute ignition, and the balance of the air required for combustion is provided through 25 the ports 22 already described. This air is preferably delivered under pressure as by a fan (not shown) or by the maintenance of a differential vacuum condition in the combustion chamber, and it will be seen that the 30 jets of air entering the combustion chamber through the ports 22 will impinge upon the fuel and flame streams at relative right angles, producing a violent mixing and 35 agitation, with a consequent violent and intense combustion which is completed within a relatively short time. The brickwork of that portion of the side walls not covered by the side water walls and the arch subject both 40 the entering fuel and the fuel and flame stream to radiant heat which promotes both the ignition and the completion of combustion. The combustion of any combustibles passing over the upper end of the arch into the space 45 above the arch is ensured by the heat radiated from the arch, so that by the time the first pass of the bank of tubes 9 is reached, combustion will have been completed, and the bank of tubes 9 will function as an economizer 50 section.

It will be seen that the provision of the groups of tubes C and the diagonal row of tubes 24 divides the combustion chamber into what is, in effect, a plurality of combustion 55 zones, and the manner of introducing and burning the fuel produces violent combustion in each of the combustion zones, in consequence of which I am enabled to thoroughly burn a larger amount of fuel per unit of volume than is possible in a structure not provided with independently functioning zones, for the reason that stream line combustion is prevented, due to the relative small size of each combustion zone unit, while, at the same 60 time, high efficiency is obtained. No trouble 65

will be encountered because of slagging of the refuse particles for such as precipitate downwardly in the spaces between the tubes 18 will remain in granular readily removable form. By virtue of the high rate at which 70 the side water walls and the tubes 24 will absorb heat, there will be no slag deposit thereon, and by the time the waste gases reach the bank of tubes 9 their temperature will be reduced below the point at which the ash carried 75 in suspension therein will fuse, in consequence of which there will be no slagging trouble encountered in the rear.

I prefer to terminate the fins 26 some distance above the drum 7. In this connection 80 it is not undesirable to have some portion of the gases pass around the lower end of the arch. This amount, however, should be comparatively small, and the length of the fins 26 should be determined in accordance with 85 the needs of the particular installation.

It will follow, from what has been said, that the boiler will develop very high capacities with an amount of evaporating surface quite small in comparison to the number of tubes which would be required in accordance with standard practice to develop the same amount of steam.

What I claim is:

1. In a stationary boiler-furnace, boiler elements arranged to form the lower part of the boiler-furnace substantially into a plurality of lateral separately functioning combustion zones, and means for feeding finely divided fuel and air into the lower part of the combustion space for intense combustion. 95

2. In combination, a pair of laterally spaced upper drums, a pair of laterally spaced lower drums, the said upper drums being positioned respectively substantially above the lower drums, tubes connecting the lower drums, tubes connecting the upper drums, tubes connecting each upper drum with its respective lower drum, whereby a box-like combustion chamber largely defined by tubes is provided, tubes diagonally connecting a lower drum with an upper drum and baffled to divide the combustion chamber into lower and upper communicating combustion spaces, and means for introducing fuel into the lower 100 space. 110

3. In combination, a pair of laterally spaced upper drums, a pair of laterally spaced lower drums, the said upper drums being positioned respectively substantially above the lower drums, tubes connecting the lower drums, tubes connecting the upper drums, tubes connecting each upper drum with its respective lower drum, whereby a box-like combustion chamber largely defined by tubes is provided, tubes diagonally connecting a lower drum with an upper drum and baffled to divide the combustion chamber into lower and upper communicating combustion spaces, and means for introducing fuel into the lower 115 space. 120

125

fuel and combustion air into the lower space under conditions to produce violent mixing and burning.

4. In a pulverized coal burning boiler combustion chamber, means introducing a stream of pulverized coal thereinto, a group of tubes extending approximately parallel to the line of fuel admission and to one side of the fuel and flame stream, said tubes being arranged to constitute in effect a channel with lateral openings, and means whereby combustion air may be supplied to the channel to pass laterally thereout through said openings.

5. In a finely divided fuel burning boiler furnace, a group of finned tubes therein arranged to of themselves constitute a channel for combustion air, the fins being interrupted to provide ports.

6. In a finely divided fuel burning boiler furnace, a tubular water screen in the lower portion of the furnace, and other tubes grouped to form channels for combustion air which rise substantially above the screen and divide the lower part of the combustion space above the screen, said channels having openings communicating with the combustion space.

In testimony whereof I have hereunto signed my name.

VIRGINIUS Z. CARACRISTI.
